United States Patent Office

Des. 182,975
Patented June 3, 1958

182,975

MUSICAL JEWEL BOX

Hester H. Robinson, St. Joseph, Mo.

Application August 26, 1957, Serial No. 47,507

Term of patent 3½ years

(Cl. D86—9)

Fig. 2.

Fig. 3.

Fig. 1 is a perspective view of the musical jewel box, showing my new design;

Fig. 2 is an end elevational view thereof; and

Fig. 3 is a rear elevational view thereof.

I claim:

The ornamental design for a musical jewel box, as shown.
